Fig. 5

Fig. 6

Fig. 7

Fig. 8

Fig. 9

FIG. 1 is a front elevational of a combined wall mounted holder and flower pots therefor showing my new design;

FIG. 2 is a side elevational view taken from the right of FIG. 1;

FIG. 3 is a top plan view of FIG. 1;

FIG. 4 is a bottom plan view of FIG. 1;

FIG. 5 is a rear elevational view of FIG. 1;

FIG. 6 is a front elevational view of a second embodiment of the design shown in FIG. 1;

FIG. 7 is a rear elevational view of FIG. 6;

FIG. 8 is a front elevational view of a third embodiment of the design shown in FIG. 1; and

FIG. 9 is a rear elevational view of FIG. 8.

The three embodiments are identical with the exception of the design on the left side of the holder.

What is claimed is:

The ornamental design for a combined wall mounted holder and flower pots therefor, as shown and described.
